UNITED STATES PATENT OFFICE.

WILHELM HAMMERSCHMIDT, OF PHILADELPHIA, PENNSYLVANIA.

GAS-ENGINE.

SPECIFICATION forming part of Letters Patent No. 288,632, dated November 20, 1883.

Application filed August 20, 1883. (No model.)

To all whom it may concern:

Be it known that I, WILHELM HAMMERSCHMIDT, a citizen of the Empire of Germany, who has resided for one year last past in the 5 United States, and declared his intention of becoming a citizen thereof, now residing at Philadelphia and State of Pennsylvania, has invented an Improvement in Gas-Engines, of which the following is a specification sufficiently full, clear, and exact to enable those skilled in the art to make and use the invention.

This invention relates to improvements in that class of gas-engines which are operated 15 by the ignition and explosion of a mixture of atmospheric air and gas; and the object is to produce a double-acting noiseless gas-motor which is simple in construction and not liable to get out of order, and very powerful.

20 In the drawings, Figure 1 represents a horizontal section of the engine, partly in plan view. Fig. 2 is a side elevation, partly in section. Fig. 3 is a cross-section on line 3 3 of Fig. 4. Figs. 4, 5, 6, and 7 are sections 25 showing the different positions of the valve and piston.

In the drawings, a cylinder, A, of suitable dimensions, according to the size and power of the engine desired, contains the piston B, 30 connected in the usual manner to the cross-head and crank on the main shaft. In said cylinder are arranged the inlet-ports a a' and an air-port, b , and on the valve-seat is placed the slide-valve C. This valve is double-faced, 35 one of its faces bearing on the valve-seat, while the other fits snugly against a cover, D, or clamping-plate, which is secured to the cylinder by stud-bolts d , provided with springs e , placed in recesses e' , so that the cover can 40 slightly yield to prevent sticking of the valve, and will yet bear with sufficient pressure against the back of the valve to prevent any leakage of air and gas. The valve is operated by a cam, eccentric, or crank, E, moving in a 45 yoke, F, which is provided with friction-rollers, to lessen the friction of the surfaces coming in contact with each other. The yoke is connected with the valve by the valve-rod G, in the usual manner, and moves it backward and 50 forward as the piston and its rod O, with the cross-head H and connecting-rod I, operate the crank K. The valve is provided with a

central inlet-port, f , having two branches, g and h , and with two exhaust-ports, i i' , passing entirely through the valve, which coincide 55 with the ports k k' in the cover, converging to a central outlet, k^2 , that leads into the atmosphere.

In the central part of the cover is arranged a port or opening, l , in which a gas-jet is continually burning, whereby the mixture of air and gas is ignited and exploded at proper intervals during the reciprocations of the engine.

The gas-inlet port m has branches n n' , which communicate with the port f and its 65 branches as the valve moves in the opposite direction.

The cylinder is surrounded by a water-jacket connected with a suitable source of water-supply, so as to produce a constant circulation of water, and thereby keep the cylinder cool. A suitable oiling apparatus is attached to the cylinder, by which it and the piston can be properly lubricated.

In the position in which the piston B is 75 shown in Fig. 1 the port a' is open to the atmospheric air and gas, which press against the piston and force it toward the left side, as shown by the arrow. The valve C remains stationary until the piston B has nearly arrived in the position shown in Fig. 4. In this case the atmospheric air and gas are cut off, and the piston continues to move by the pressure of the mixture. The flame is then drawn into the cylinder from the port l and through the 80 inlet-port a' , and ignites the mixture of air and gas and forces the piston forward to complete its stroke, as illustrated in Fig. 5. A vacuum is then created after the explosion of the gases, which causes the piston to commence 85 its return-stroke, which is completed, as in the first instance, by the admission of the mixture and its explosion. In the position shown in Fig. 6 the products of combustion are escaping into the atmosphere, immediately after 90 which the slide-valve closes the ports a' , i' , and k' , and the ports a , i , and k are opened. As the valve is now moved in the opposite direction by means of the cam and yoke on the main shaft, the ports on the opposite 95 end of the cylinder, valve, and cover are opened, and communicate with each other as in the first operation, and the piston is driven 100 in the opposite direction.

It will thus be seen that the engine is made double-acting, and much more power can be obtained with a small expenditure of gas; also, that the atmospheric air and gas are drawn 5 into the cylinder and operate the piston during the first part of the stroke, and are ignited then, to complete the stroke, with far more force than if exploded at the beginning of the stroke, as is ordinarily the case.

Having thus described my invention, what I 10 claim, and desire to secure by Letters Patent, is—

1. The combination, substantially as described, of a cylinder, a double-faced slide- 15 valve provided with two exhaust-ports and

with an intermediate branched supply-port, and a cover provided with two exhaust-ports, with an intermediate branched gas-supply port, and with a central flame-port.

2. In a gas-engine, the combination of a 20 cylinder provided with inlet and outlet ports, a slide-valve having a branched port, *f*, and outlet-port *i i'*, and a self-adjusting cover provided with gas-ports and two outlet-ports, substantially as described.

WILHELM HAMMERSCHMIDT.
